UNITED STATES PATENT OFFICE.

JOHN G. REDFORD, OF MILWAUKEE, WISCONSIN.

SOUND-REPRODUCING INSTRUMENT.

Application filed February 14, 1920. Serial No. 358,775.

To all whom it may concern:

Be it known that I, JOHN G. REDFORD, a citizen of the United States, and resident of Milwaukee, in the county of Milwaukee and State of Wisconsin, have invented new and useful Improvements in Sound-Reproducing Instruments, of which the following is a description, reference being had to the accompanying drawings, which are a part of this specification.

The invention relates to sound reproducing instruments.

As generally constructed the motor or actuating mechanism of a talking machine is placed close to the amplifier so that sounds produced by the operation of the motor come in contact with the outer wall of the amplifier and both restrict and confuse the normal and desired function of the amplifier, resulting in a pronounced interference with the musical effect of a record. Also the vibrations of the motor produce sound waves interfering with the reproducer. To overcome these difficulties I have provided a casing fitting closely about the motor and between the top of the cabinet and the amplifier and provided with a sound deadening lining which also covers the top of this casing. Such a construction sufficiently insulates the motor and prevents sounds produced by the motor's operation from being heard direct, or interfering with the proper action of the amplifier and reproducer.

A further object of the invention is to so shape the motor enclosing housing as to prevent its walls acting as a sound board.

The invention further consists in the several features hereinafter set forth and more particularly defined by claims at the conclusion hereof.

In the drawings: Fig. 1 is a vertical sectional view through sound reproducing apparatus embodying the invention; Fig. 2 is a detail bottom view of the motor housing, parts being broken away and parts being shown in section; Fig. 3 is an end view of the motor housing.

In the drawings the cabinet has a body portion 1 and a removable cover 2. Within the body portion is a top 3 having an aperture therein with flanged seats to receive a removable top portion 4 carrying the usual motor or actuating mechanism 5 on its lower side connected to rotate the usual turntable 6 located within the top of the cabinet formed by the cover 2 and the top 3, 4.

A tone arm 7 carries and communicates with a reproducer 6' at one end and with a horn or amplifier 7' at its other end. This amplifier is disposed within the body portion of the cabinet and is generally made of wood and while vibrations are set up in it by the sound from the reproducer, the motor mechanism also produces vibrations which interfere with these sound vibrations of the amplifier and also of the reproducer.

To prevent vibrations from the motor mechanism affecting the purity and clearness of the desired sound vibrations from the reproducer and the amplifier, I provide a housing or casing 8 closely fitting around the motor mechanism and having upper flanged edges 9. This housing is provided with a lining 8' of sound deadening material, such as canton flannel. I have shown two layers of this material secured to the walls of the housing and said flannel is placed with the fleece or nap side facing out. On the bottom of the top portion 4 I provide a cover 10 of suitable sound deadening material, the outer edges of which are interposed between the portion 4 and the flanged edges 9 to form a soundproof joint between the housing and the top. The housing 8 is secured to the top by screws 11 or other suitable fastening means. The bottom and end walls of the housing are preferably formed in a continuously curved surface so as to prevent the walls of the housing acting as a sounding board to give off objectionable vibrations received from the actuating mechanism.

Where the winding shaft 12 and the speed control rod 13 pass through openings in the housing 8 I provide washers 14 of sound deadening material, such as canton flannel or felt having portions closely fitting these members to prevent the motor sounds passing out into the cabinet. These washers may also be formed by extending portions of the sound deadening lining 8' beyond the edges of the opening in the housing.

From the foregoing description it will be noted that the means for deadening the sound of the actuating mechanism prevents interference of the vibrations from said mechanism with the proper functioning of the amplifier and reproducer.

I desire it to be understood that this invention is not limited to any specific form or arrangement of parts except in so far as such limitations are specified in the claim.

What I claim as my invention is:

A muffler for sound-reproducing machines of the type having a cabinet and actuating mechanism carried on the bottom of the top of the cabinet, comprising a housing enclosing said actuating mechanism and having flanged edges and a curved surface forming its bottom and opposite end walls, sound deadening material lining the walls of said housing and covering its top and the flanged

edges thereof so as to completely sound-insulate the interior of the housing, and fastening means passing through the flanged edges of the housing and the sound-deadening material between it and the top for securing said housing to the top of the cabinet.

In testimony whereof, I affix my signature.

JOHN G. REDFORD.
